BATTERY LIFTING AND CARRYING DEVICE

Helmer C. Moen, St. Paul, Minn.

Application September 12, 1936, Serial No. 100,565

3 Claims. (Cl. 294—103)

The object of my invention is the provision of a simple, safe and strong, battery lifting and carrying device adapted to accommodate itself to battery posts of different diameters and to securely clamp and hold itself on said posts, without liability of slipping, when tension is placed on its handle strap in the act of lifting and sustaining the weight of a battery.

To the attainment of the foregoing the invention consists in the improvement as hereinafter described and definitely claimed.

In the drawing accompanying and forming part of this specification:—

Figure 1 is a plan view of the device constituting the preferred embodiment of my invention, said device being shown in proper relation to a battery the outline of which is indicated by dotted lines.

Figure 2 is an enlarged side elevation showing one of the clamps of my device in association with a portion of the handle strap.

Figure 3 is an inner end elevation of the same.

Figure 4 is a perspective of the body of one clamp.

Figure 5 is a perspective of the movable jaw of the clamp.

Figure 6 is a perspective of the clamp lever.

Figure 7 comprises disconnected perspectives showing one end portion of the handle strap and the complementary bail for pivotally connecting said end portion to the cross rod in the lever.

Similar numerals of reference designate corresponding parts in all of the views of the drawing.

In Figure 1 a battery 1 is represented by dotted lines, said battery being equipped with conventional spaced terminal posts 2.

By reference to Figure 1 it will be understood that my novel battery lifting and carrying device comprises a handle strap 3 of leather or other appropriate material, metallic bails 4 on the end portions of the handle strap 3, and connecting clamps 5 coupled to the end portions of the handle strap 3 through the medium of the bails 4. The clamps 5 are similar in construction, and, therefore, a detailed description of the clamp illustrated in Figures 2 to 6 will suffice to impart a definite understanding of both clamps.

By reference to the figures specifically alluded to, the clamp shown therein will be understood as comprising a body, Figure 4, having a bottom wall 6 with an opening 7 therein, side walls 8, preferably though not essentially, of the taper form shown, and a transverse rod 9 interposed between and connecting and bracing the side

walls 8, and spaced above the bottom wall 6. Said clamp will also be understood as comprising in addition to the body described, a clamping jaw 10, Figure 5, and a lever 11, Figure 6. The jaw 10 is pivotally connected to the lever 11 through the medium of a pin 12, and said lever 11 is pivotally mounted on a transverse pin 13 carried in the rear upper portion of the body. By particular reference to Figure 5 the jaw 10 will be understood as being in the form of a plate 14 with an arcuate recess 15 in its outer end and with side flanges 16 terminating in apertured ears 17 through which the pin 12 extends. Figure 2 shows the disposition of the jaw 10 in the clamp body and the interposition of the flanged portion of the jaw between the bottom wall of the body and the beforementioned rod 9. The lever 11 is of general inverted U-shape, and it is provided in each of its side portions 18 with apertures 19 and 20 and also with an aperture 21; the apertures 19 and 21 receiving the beforementioned pins 12 and 13, respectively, and the apertures 20 receiving the pin 22. The pin 22 is disposed in the bight of the bail 4 and is connected through the medium of the said bail 4 with the adjacent end portion of the handle strap 3. Manifestly when the device is applied as shown in Figure 1 and the handle strap 3 is moved upwardly as in the lifting of the battery, the jaws 14 will be powerfully moved outwardly and set against the battery posts 2 so as to powerfully clamp the said battery posts against the outer portions of the walls of the openings 7 in the body, and it will be appreciated that the heavier the battery the more securely will the posts 2 be clamped. It will also be appreciated that the foregoing is true of battery posts of different diameters, and that the device when a battery is set down is susceptible of being expeditiously and easily disengaged from the posts 2.

While I have specifically described the preferred embodiment of my invention it is to be understood that in practice such changes or modifications may be made in the construction as fairly fall within the scope of my invention as claimed.

Having described my invention, what I claim and desire to secure by Letters Patent is:—

1. The herein described battery lifting and carrying device comprising a handle strap, bails connected to and having their bights extended beyond the ends of said strap, and clamps at the ends of the handle strap, each of said clamps made up of a body with a bottom wall and side

- walls and with an opening in the outer portion of the bottom wall and further with a cross rod extending between the side walls and spaced above the bottom wall, a jaw with side flanges and an arcuate recess in its outer end, interposed between the bottom wall of the body and said cross rod and having at its inner end apertured ears, a lever of inverted U-shape pivotally mounted between the side walls of the body and pivotally connected to the said ears of the jaw, and a pin carried by said lever and disposed in the bight of the adjacent bail.
2. The combination in a battery lifting and carrying device, of a handle strap, and a post clamp at the end of the strap, the post clamp including a body with a bottom wall and side walls and also with an opening in the bottom wall, and a guide portion spaced above the bottom wall, a jaw slidable between the bottom wall
- 6
- 10
- 15

and guide portion of the body and having a recess in its outer portion, and a U-shaped lever mounted between the side walls of the body and pivotally connected to the jaw and also pivotally connected to the handle strap.

3. A battery lifting and carrying device of the type in which battery pole engaging means are carried at the ends of a handle strap, characterized by battery pole engaging means comprising essentially a body with an opening to receive a battery pole, a jaw slidable relatively to said opening, and a lever pivotally connected to the body and also pivotally connected to one end of the handle strap and to said jaw, the pivotal connection of the lever to the body being at a point between the pivotal connection of the lever to the handle strap and the pivotal connection of the lever to the jaw.
